REEL

Oliver Oscar Carlson, Bend, Oreg.

Application July 31, 1939, Serial No. 287,591

7 Claims. (Cl. 242—110)

My invention relates to reels on which coils of wire, cable and the like are wound, or on which coils may be placed in order to be unwound as used.

5 When wire, or the like, is wound in coils on reels it is often desirable to remove such coils from the reels entirely, without unwinding the coils, but this is done only with considerable difficulty with ordinary types of reels or spools and 10 generally necessitates the complete destruction of the reel or spool or, at least, the prying off of one of the side disks of the reel, rendering the reel unfit for further service. Furthermore, difficulty is often experienced in removing the core 15 of the reel from within the coil of wire or other material when the wire or other material has been tightly wound on the reel.

When a previously wound coil of wire, which is not on a reel, is to be used, it is desirable to 20 place the same on a suitable dispensing or payout reel to keep the coil together and in place and to facilitate the dispensing or paying-out of the wire as it is used. For this purpose it is necessary, not only to have a reel with a core 25 on which the wound coil may easily be slid, but also to provide a reel with an adjustable core to fit coils of various size and to hold the coil securely on the core.

An object of my invention, therefore, is to provide 30 a reel from which the coil of wire, cable or other material may be removed easily and without damage to the reel, and on which a previously wound coil may be placed and securely held for dispensing.

35 This object I accomplish by forming my reel with a side wheel or disk which is removable from the core and further by making the core itself adjustable and collapsible so that the core can be reduced in size to permit the coil to be 40 slipped off or on the core when one of the side disks is removed.

Another object of my invention is to provide a reel on which coils of various diameters may be wound, or may be placed for unwinding, and 45 this object I attain by so arranging the core that its diameter may be varied by a simple manipulation of the side disks or wheels.

A further object of my invention is to provide a reel on which coils of various widths may be 50 wound, or placed for unwinding, and this object I accomplish by making the distance between the two side disks or wheels, which constitute the sides of the reel, readily adjustable on the core.

A still further object of my invention is to provide 55 an adjustable reel of the type above indi-

cated which can be made strong enough for practical use with heavy wire and the like, but which will still be simple in construction and not costly to manufacture.

The manner in which I attain these and incidental objects will be apparent from the following description with reference to the accompanying drawing.

In the drawing:

Fig. 1 is an end elevation of the reel, a portion of this figure being shown in section for the purpose of illustrating the construction more clearly;

Fig. 2 is a sectional plan taken on the lines 2—2 of Fig. 1 and looking in the direction indicated by the arrows;

Fig. 3 is a sectional plan taken on the line 3—3 of Fig. 1 and looking in the direction indicated by the arrows; and

Fig. 4 is a fragmentary elevation, partly in section, and drawn to a larger scale showing the means for supporting one of the bars constituting the core in the construction shown in Fig. 1.

A dished plate 18 having a peripheral flange 19 and a central hub 20 has a stub-shaft 21 firmly secured in the central hub 20 and is provided with a series of radial bars 22 symmetrically arranged and rigidly secured to the hub 20 and to the flange 19. Each of the bars 22 has a bracket 23 slidably mounted thereon, the bars 22 being bent to conform with the interior of the recessed plate 18, substantially as shown in Figs. 1 and 2. The sliding brackets 23 are arranged to carry perpendicular arms or rods 24, the bottoms of which arms are secured to the brackets in any suitable manner, for example, they may be secured on threaded stems 25 formed integral with the brackets as shown in Fig. 4. The arms 24 are thus movable radially towards or away from the central hub 20.

A pair of identical wheel-like members 26 and 27 constitute the sides of the reel and form the supports for the adjustable core constituted by the arms 24. Each of the wheel-like members comprises a central hub 28, bored to slide on the stub-shaft 21, a rim 30, preferably made of pipe or tubing, and a series of supporting curved rods 31.

The curved rods 31 correspond in number to the arms 24 and are arranged symmetrically about the hub 28, being rigidly secured to the hub 28 and to the rim 30 by welding or any other suitable means. These rods 31 are so shaped that when symmetrically arranged they will form with each other a series of curved guideways 32 for accommodating the arms 24, and these guideways 55

are adapted to cause the arms 24 to be moved simultaneously towards or away from the central hubs when the wheels are particularly rotated on the stub-shaft 21. Slotted-head set screws 29 are provided for the purpose of holding these wheels rigidly in place on the stub-shaft 21.

When my reel, made in this manner, is to be assembled for use, the brackets 23 and their attached arms 24 are arranged so that their centers lie in a circle about the hub 20, as shown in Fig. 2. The wheel-like member 26 is then placed on the stub-shaft 21 with an arm 24 in each of the guideways 32, and slid on the stub-shaft until the member 26 is adjacent the dished plate 18. A washer 33 is preferably interposed between the hub 20 of the dished plate and the hub 28 of the wheel-like member 26 to facilitate subsequent turning of the wheel 26 with respect to the dished plate 18. The wheel-like member 26 is rotated until the arms 24 form a core of the desired diameter, whereupon the slotted-head set screw 29 is tightened to retain the wheel 26 in this position on the stub-shaft 21. Then the other wheel-like member 27 is placed on the stub-shaft 21 with its guideways in registration with those of the wheel-like member 26 and thus with the arms 24 extending thru its guideways. The wheel-like member 27 is then secured in place by the tightening of the set screw 29. I consider my reel when constructed in this manner particularly suitable for use where large diameter reels are required because of its skeleton construction.

When the wire or other material has been wound on the reel and it is desired to remove the entire coil, the member 27 is removed from the stub shaft 21 and the slotted-head set screw 29 of the member 26 is loosened and the member 26 is then given a slight turn on the stub shaft 21 so as to cause the arms 24 to be moved slightly towards the center of the reel, and thus relieve all tension on the coil, which may then be readily lifted off.

Similarly when a coil of wire is to be placed on the reel for dispensing, the member 27 is first removed; the set screw 29 of member 26 is loosened and the arms or core rods 24 are moved by the turning of member 26, until these arms lie in a circle slightly smaller in diameter than the interior of the coil. When the coil is placed on these arms and the member 27 is replaced, the arms are then moved outwardly as far as possible by the turning of the members 26 and 27 so that the arms will hold the coil tightly in place. The set screws 29 in the members 26 and 27 are then tightened so that these members, and with them the arms 24 will be held in this position.

Obviously modifications might be made in the construction of details of the various parts of my reel without departing from the principles of my invention. This is particularly true in the construction of the wheel-like members 26 and 27 and also in the mounting for the arms or core rods 24 on the radial bars 22. It is not my intention to restrict the construction of the particular members in my reel or to limit my invention in this regard otherwise than as set forth in the attached claims.

I claim:

1. In a reel of the character described, an outer member, a central shaft secured to said outer member, a plurality of similar arms movably mounted on said outer member, said arms extending inwardly from said outer member parallel to said central shaft, a pair of reel side mem-

bers mountable on said central shaft, each of said reel side members having a central hub and means for securing said hub firmly in place on said central shaft, each of said reel side members having a series of equally spaced curved guideways corresponding in number to said arms through which said arms extend. 5

2. In a reel of the character described, an outer member, a central shaft carried by said outer member, a plurality of equally spaced radial bars 10 carried by said outer member, an arm slidably mounted on each of said bars, said arms extending parallel to said central shaft, a pair of reel side members mountable on said central shaft, each of said reel side members having a central hub and means for securing said hub firmly in place on said central shaft, each of said reel side members having a series of curved guideways corresponding in number to said arms through which 15 said arms extend, said guideways being identical 20 in curvature and said guideways arranged symmetrically on said reel side members.

3. A reel of the character described comprising an outer member, a central shaft secured to said outer member and perpendicular to the plane of said outer member, a plurality of similar arms 25 movably mounted on said outer member, said arms extending inwardly from said outer member parallel to said central shaft, said arms thereby 30 being movable radially, inwardly and outwardly with respect to said central shaft, a pair of reel side members mounted on said central shaft, each of said reel side members having a central hub and means for securing said hub firmly in place 35 on said central shaft, each of said reel side members having a series of equally spaced curved guideways corresponding in number to said arms through which said arms extend, the curvature 40 of said guideways being sufficiently great to prevent said arms moving in said guideways when one of said reel side members is firmly secured on said central shaft, but causing radial movement of said arms when said reel side members are partially rotated on said shaft. 45

4. A reel of the character described comprising a cup-shaped outer member, a central shaft secured to said outer member, a plurality of equally spaced radial bars carried by said outer member, 50 an arm slidably mounted on each of said bars, said arms extending parallel to said central shaft, said arms thereby being movable radially, inwardly and outwardly with respect to said central shaft, a pair of reel side members mounted on said central shaft, each of said reel side members having a central hub and means for securing said hub 55 firmly in place on said central shaft, each of said reel side members having a series of equally spaced curved guideways, the curvature of said guideways being sufficiently great to prevent said arms moving in said guideways when one of said reel side members is firmly secured on said central shaft, but causing radial movement of said arms when said reel side members are partially 60 rotated on said shaft.

5. In a reel of the character described, an outer member, a central shaft, a plurality of similar arms movably mounted on said outer member, said arms extending inwardly from said outer member parallel to said central shaft, a pair of disks 70 mountable on said central shaft, each of said disks having a central hub and means for securing said hub firmly in place on said central shaft, each of said disks having a series of equally 75

spaced curved slots corresponding in number to said arms through which said arms extend.

6. In an adjustable reel of the character described, a central shaft, a plurality of equally-spaced radial arms extending from said central shaft in a plane perpendicular to said shaft, reel core rods slideably mounted on said radial arms and extending parallel to said central shaft, a wheel-like member rotatably mounted on said central shaft, said member having a rim and a hub and a series of curved members symmetrically arranged connecting said hub and said rim corresponding in number to said core rods and engaging and controlling the movement of said core rods, and means for securing said hub against rotation on said central shaft.
- 5
- 10
- 15

7. In an adjustable reel of the character described, a central shaft, a plurality of equally-spaced radial arms extending from said central shaft in a plane perpendicular to said shaft, said arms rigidly secured to said shaft, a reel core rod slideably mounted on each of said radial arms and extending parallel to said central shaft, a reel side member slideably and rotatably mounted on said central shaft, said member having a series of curved members symmetrically arranged 10 lying in a plane perpendicular to said central shaft corresponding in number to said core rods and engaging and controlling the movement of said core rods, and means for securing said reel side member in place on said central shaft. 15
